UNITED STATES PATENT OFFICE.

EUGENE SCHNEIDER, OF PARIS, FRANCE, ASSIGNOR TO SCHNEIDER & CIE., OF PARIS, FRANCE, A LIMITED JOINT-STOCK COMPANY OF FRANCE.

FIRING MECHANISM FOR GUNS.

Application filed July 26, 1921. Serial No. 487,681.

To all whom it may concern:

Be it known that I, EUGENE SCHNEIDER, a citizen of the Republic of France, residing at 42 Rue d'Anjou, Paris, France, have invented new and useful Improvements in Firing Mechanisms for Guns, which is fully set forth in the following specification.

This invention consists in various improvements on the invention of the firing mechanism composed of a combined striker-carrier and firing tube holder for the breech mechanism of guns for which a patent was sealed under No. 1,310,887.

The present improvements are illustrated in the accompanying drawings in which:—

Fig. 1 is a sectional elevation along the axis of a striker-carrier combined with a firing tube holder.

Fig. 2 is a front elevation showing the firing tube holder lifted up to allow of the insertion of a new firing tube.

Fig. 3 is a developed section on the line 3—3 of Fig. 2.

This improved constructional form is characterized by the feature that the pivot pin C, by means of which a disc A constituting the firing tube holder proper is pivoted to the body B of the striker-carrier, instead of being fixed, that is to say attached to the said body B, is movable longitudinally in the latter in such a manner as to be capable of projecting from the striker-carrier to an extent that varies according to the thickness of the base of the firing tube.

A spring D assures nevertheless in all cases a perfect bearing of the firing tube against the body of the striker-carrier.

It will be readily understood that if the firing tube E were to be replaced by a new firing tube whose base e would be slightly thicker than that of the firing tube that has just been removed, the bearing of the new firing tube would be perfectly assured at the cost of a simple supplementary pressure of the spring D.

This arrangement of spring pivot C—D which is movable longitudinally allows on the other hand of simplifying the mounting of the disc A upon the body of the striker-carrier. For this purpose it is sufficient to provide the lodgment for the base e in the disc A in such a manner that in all cases the said base shall project to the rear of the disc, and to provide on the other hand in the body B of the striker-carrier a central recess b

adapted to receive the said projection of the base of the firing tube.

In the rotational movement which is imparted to the disc A in order to bring the new firing tube, which has just been inserted in the said disc, into its operative position, the projection of the base of the firing tube strikes a chamfer b¹ over which it slides and thereby detaches the disc A slightly from the striker-carrier B, compressing for this purpose the spring D. Then the said projection of the base enters the recess b, and the spring D expands and thus assures the bearing of the firing tube upon the said body B of the striker-carrier.

In order that the movement of raising the disc A for the purpose of removing the firing tube, shall be easily effected, a chamfer b² is formed on the edge of the recess b.

I claim:—

1. A firing mechanism for guns comprising, in combination, a striker-carrier, a pivot pin slidably mounted in said carrier, a firing-tube holder eccentrically pivoted to said striker-carrier by means of said pin, and a spring operatively engaging said pin and tending to move said pin rearward relative to said striker-carrier.

2. A firing mechanism for guns comprising, in combination, a striker-carrier having a recess in one end thereof, a pivot member resiliently mounted in said striker-carrier, and a firing-tube holder carried by said member, said recess being adapted to receive the base of a firing tube whereby angular movement of said holder is prevented.

3. A firing mechanism for guns comprising, in combination, a striker-carrier, a pivot pin slidably mounted in said striker-carrier, a firing-tube holder eccentrically mounted on said pin and having angular movement relative to said striker-carrier, and a spring normally tending to move said holder rearward relative to said striker-carrier.

4. In a firing mechanism for guns, the combination of a striker-carrier having a chamfer at one end thereof, a firing tube holder pivoted thereto, to swing transverse to the axis of said carrier, and a pivot pin resiliently mounted in said striker-carrier for supporting said holder, said chamfer being positioned in the arcuate path of said holder.

5. In a firing mechanism for guns, the combination of a striker-carrier having a

chamfer and a chamfered recess in one end thereof, an element mounted in the striker-carrier for relative longitudinal movement thereto, and a firing tube holder carried by 5 said element, said chamfer and chamfered recess being adapted to facilitate the placing of a firing tube in firing position.

6. In a device of the class described, a striker-carrier, a pivot pin mounted in said 10 striker-carrier for relative longitudinal

movement thereto, a resilient member positioned to coact with the pivot pin, and a firing tube holder carried by said pin.

In testimony whereof I have signed this specification.

EUGENE SCHNEIDER.
